UNITED STATES PATENT OFFICE.

ARCHIBALD FERGUSON REDDIE, OF PHILADELPHIA, PENNSYLVANIA, ASSIGNOR TO WILLIAM H. McCALLUM AND IRVING McCALLUM, OF SAME PLACE.

DESIGN FOR CARPET-BORDER.

SPECIFICATION forming part of Design No. 24,226, dated April 16, 1895.

Application filed March 4, 1895. Serial No. 540,534. Term of patent 3½ years.

To all whom it may concern:

Be it known that I, ARCHIBALD FERGUSON REDDIE, a citizen of the United States, residing at the city of Philadelphia, in the county of Philadelphia and State of Pennsylvania, have invented and produced a new and original Design for a Border for a Carpet or other Fabric, of which the following is a specification, reference being had more particularly to the accompanying drawing, illustrating the same and forming part hereof.

The design of my invention may be applied to or wrought in Brussels, velvet, Wilton or other carpeting in such colors and combinations of colors as may be desired and I do hereby declare that the various shapes and figures which appear on the surface of the accompanying drawing are the expression of my design and that said drawing presents to the eye of the observer such a clear understanding of my new and original design as is sufficient to enable such person to fully understand it.

What I claim as my invention, and desire to secure by Letters Patent, is—

The design for a carpet border substantially as shown in the drawing accompanying this specification.

In testimony whereof I have hereunto signed my name.

ARCHIBALD FERGUSON REDDIE.

In presence of—

ANNA K. MAY,
HARRY O. SWEARER.
